UNITED STATES PATENT OFFICE.

JAMES LUTTED, OF BUFFALO, NEW YORK.

MACHINE FOR MAKING CONFECTIONS.

SPECIFICATION forming part of Letters Patent No. 284,136, dated August 28, 1883.

Application filed June 8, 1883. (No model.)

To all whom it may concern:

Be it known that I, JAMES LUTTED, a citizen of the United States, residing in Buffalo, in the county of Erie and State of New York, 5 have invented certain new and useful Improvements in Machines for Making Confections, of which the following is a specification.

My invention relates to certain new and useful improvements in machines for making 10 gum, cream, and grained work, or other similar candies, all of which will be fully and clearly hereinafter shown by reference to the accompanying drawings, in which—

Figure 1 is a side elevation; Fig. 2, a plan 15 or top view. Fig. 3 is an enlarged vertical-longitudinal section through the stock-box and a portion of the mechanism for lifting the valves. Fig. 4 is an end view of a portion of the molding mechanism and a similar view 20 of one of the mold-boxes. Fig. 5 is a side elevation of a portion of the mechanism for moving the mold-boxes forward after being placed in position. Fig. 6 is a front elevation of the same, and Fig. 7 is a sectional elevation of a portion of the mold-box, showing 25 one of the valves open and the stock about to drop out.

The frame a of the machine is constructed of cast-iron or other suitable material, and is 30 secured together by binding-rods in the usual way. It is provided with uprights or vertical side pieces, a' , having openings a^2 to receive the projecting ends a^3 of the molding-plate, cross-head, or bed a^4 . The cross-head 35 a^4 receives a vertical movement up and down by means of the angle-arms a^5 a^6 , the two being formed in one piece, which are secured to a shaft, a^7 , and to each side of the machine by boxes b .

40 b' b'' are connecting-rods, one on each side of the machine, jointed to the arms a^6 by pins b^3 . Their opposite ends are connected by crank-pins b^3 to the wheels b^4 .

To the arms a^6 are jointed, by pins b^5 , the 45 connecting rods or arms b^6 , the upper ends of which are jointed by a pin, c , to the molding-plate cross-head a^4 . It will now be seen that a revolution of the wheels b^4 will cause the cross-head to move vertically up and down.

50 The molds c' are either connected, in any suit-

able way, to the mold-plate c^3 ; or may be made to form a part of it. The mold-plate c^3 is hinged by a joint or hinge, c^4 , to the cross-head a^4 , and is held at the opposite side by bolts c^5 , (shown in Fig. 4.) The bolts pass 55 easily through holes in the cross-head, their movement being limited by the heads of the bolts. This arrangement gives the mold-plate and mold-patterns a slight movement on the hinges c^4 , or as much as the length of the bolt 60 c^5 will allow, so that when the cross-head is brought down the molding-patterns will pass into the material of which the molds are made—powdered starch, for instance, which is generally used—and make the molds. This 65 operation brings the mold-plate close up to the face of the cross-head, and as the cross-head moves upward one side, c^6 , of the molding-plate, moves up a short distance, while the opposite side remains stationary for a short 70 time, thereby drawing the mold-patterns partly out of that side of the starch-box first. The object in doing this is to allow the air to enter gradually and prevent the molds from being destroyed, which it will be seen would be the 75 case if all were quickly drawn out at once and a partial vacuum formed, as the starch of which the molds are formed is a very light material, and consequently they are easily spoiled. The starch or other suitable mold-80 ing material is put into the shallow boxes d , which are all made of the same dimensions, the size being suited to the size of the machine.

d' is the starch material in the boxes. The 85 mold-patterns may be cone-shaped, or of any other form or shape that may be desired to mold candies, or any other articles the machine may be adapted to make. The boxes d for holding the molding material receive their 90 movements from a short arm, d' , rigidly secured to the pin b^3 . The object of the arm d' is to locate the pins d^3 , so that their movement shall be behind the pins b^3 , and thereby prevent the movement of the mold-boxes forward until the mold-patterns c' are up far enough to be out of the way. d^4 is a connecting-rod jointed to the pin d^3 and at the opposite end to the shaft d^5 . The shaft d^5 works in boxes d^6 in slideways e on each side of the ma- 95 100

chine, and is provided with pushing-hooks e' , and near the center is an arm, e^2 . The boxes d^6 are provided with outwardly-projecting pins e^3 to limit the backward turning movement of the hooks.

E' is a shaft rigidly fastened to the frame. Between the boxes d^6 is a rubber, or other spring, d^8 , which presses against the shaft on one side and against the boxes on the other side. (See Fig. 6.) Its object is to create sufficient friction to hold the shaft from turning too easily. It will now be seen that as the wheels b^4 turn they will give the shaft d^8 a reciprocating movement, and that when near the end of its backward movement, the arm e^2 will strike against the stationary shaft e^4 and cause the shaft d^8 to turn so as to bring the front faces of the pushing-hooks e' vertical, or nearly so. The stock-box e^5 is made of iron or other suitable material. It is connected to the machine by a frame e^6 , and is capable of being adjusted up or down by means of two hand-wheels f and screw-rods f' , which screw into projecting pieces, f^2 , on the stock-box, the rods f' being secured to the frame of the machine (see Fig. 1,) by shoulders f^3 , so as to allow it to turn therein and move the stock-box up or down, but to prevent it from moving longitudinally.

In Fig. 2, I have shown V-shaped slideways, and corresponding grooves f^4 , to keep the stock-box in line vertically. Within the stock-box is a series of valves, f^5 . They may be made either of rubber, metal, or other suitable material, and are adapted to fit and close the openings in the nozzles f^6 . (See Fig. 3.) They are fastened to the vertical rods or bars g , and are all kept in a vertical line by being passed up through the perforated plates g^1 g^2 . The plate g^1 is secured to the upper part of the stock-box by arms or other equivalent connections g^3 . Each of the vertical rods g are provided with a spiral spring, g^4 , the upper parts of which press against the under side of the plate g^1 , and the lower portions against a pin, g^5 , through the rods, the tendency of the springs being to keep the valves all down and close the openings in the nozzles. The upper plate, g^2 , (see Figs. 1 and 3,) is provided with pins g^6 , to which connecting-rods h are jointed one on each side of the stock-box. The lower ends of the rods or arms h being jointed to levers or arms h' , which are secured to the frame e^6 by a pin h^2 , the opposite end of the levers h' rest on or near the periphery of the wheels b^4 . On the wheels b^4 is a cam, h^3 , one on each wheel, which cams may be made adjustable, if desired, by being screwed onto the wheel, so they may be moved outward from the center in any well-known way. The upper ends of the rods g are each provided with pins 97 to prevent the plate g^2 from being drawn off from them during the operation of the machine.

The operation of my invention will be understood by reference to Figs. 1 and 3. The

boxes d are placed on the table, and as the wheels b^4 turn the feeding-hooks carry them forward first under the printing or molding plate, and as the next box is put in place and pushed forward the preceding box is pushed forward under the stock-box. It will be seen that when the boxes have reached their farthest point of movement forward and the feeding or pushing hooks e' are on their return movement, the boxes will remain stationary while the patterns are being forced down so as to form the molds, and the stock is being deposited in the molds in the box directly under the stock-box. The required amount of stock is dropped into the molds by the cams h^3 , lifting the arms h' , and consequently the arms h and plate g^2 . This operation lifts the valve-rods and valve f^5 , (see Figs. 3 and 7,) so that a small amount of stock, h^5 , shown in Fig. 7, drops out and fills the molds, after which, as the cams pass by, the valves all drop and suddenly cut off the supply or close the openings until the mold-box passes out and another takes its place. i represents a coil of steam-pipe. (See Fig. 3.) It is secured in any well-known way in place to the machine, so that the stock-box may be adjusted freely up and down within it, or it may be secured in the usual way to the frame e^6 , and is provided with the usual stop-cock, i' , for admitting steam, its object being to keep the stock warm during the operation of the machine, and a coil of steam-pipe or any other well-known means may be used for that purpose.

If desired, the connecting-rods b^4 d^8 may be removed, and also the wheels b^4 and cams h^3 , in which case the movements of the boxes d , the printing of the molds, and dropping of the stock into them may be all done by hand. In this case the boxes could be fed in by hand and pushed forward one after the other to the proper point, after which the printing of the molds could be done by the foot on the foot-step i^3 , and the dropping could be done by lifting the ends of the arms or levers h' . The object in adjusting the stock-box vertically is that different kinds of stock requires to be dropped from different heights, or the same kind of stock under different conditions may require a different adjustment of the starch-box.

I claim as my invention—

1. In a machine for making confections, the frame a , having the vertical side pieces, a' , a vertically-movable plate or bed provided with a pattern-plate, c^3 , and patterns for forming the molds in the boxes d , as specified, in combination with a stock-box having a series of valves for opening or shutting off the supply, a cam and connections for operating them, and a suitable feeding mechanism, substantially as described.

2. In a machine for making confections or similar articles, the combination of a cross-head or bed, a^4 , and a suitable mechanism for giving it a vertical reciprocating movement, substantially as described, with a hinged pat-

tern-plate provided with a bolt, c^5 , for limiting its movement, for the purposes specified.

3. The combination of the stock-box arranged in a suitable holding-frame, so as to have a movement up or down, with the screw-rods f' secured to the frame a , substantially as specified, and provided with the hand-wheels f , or other equivalent device for adjusting the box vertically up or down, for the purposes described.

4. The stock-box e^5 , provided with nozzles f^6 , valves f^5 , and valve-rods secured in vertical guideways, in combination with the springs g^4 for closing the valves after being released by the cams.

5. In a machine for making confections, the wheels b^4 , connecting-rods d^4 , the shaft d^5 , provided with the pushing-hooks e , and arranged in boxes, d^6 , having pins, e^6 , in combination with the arm e^2 , and stationary rod e^4 , for the purpose of feeding the boxes, substantially as described.

6. The frame a , having the vertical side pieces in combination with a cross-head, a^4 , connecting-rods b^6 , arms $a^5 a^6$, and foot-steps i^3 , for giving a vertical up and down movement, substantially as described.

7. The combination of the stock-box having the valves and their connecting-springs and parts, substantially as specified, with the jointed levers h' and connecting-rods h , for the purpose of operating the valves by hand, as described.

8. In a machine for making confections or similar articles, a stock-box provided with a series of valves and springs for operating them one way, connecting-rods h and jointed levers or arms h' , in combination with the driving-wheels provided with cams, for operating them the other way, substantially as described.
